HAYSTACK COVER

Elmer D. Abramson, Ladue, Mo., assignor to Central States Paper & Bag Company, a corporation of Missouri

Application March 13, 1950, Serial No. 149,269

6 Claims. (Cl. 108—3)

1

This invention relates in general to certain new and useful improvements in water-proof covering sheets and, more particularly, to haystack covers.

It is a primary object of the present invention to provide a covering sheet of the type stated which is economical in construction and, despite comparative low cost, is nevertheless rugged, durable, and highly water-proof.

It is a further object of the present invention to provide a covering sheet of the type stated which is relatively light in weight and can be folded up compactly for shipment and for storage pending original use or reuse.

Is an additional object of the present invention to provide a tarpaulin-like cover for haystacks and the like which sheds rain efficiently and does not become moldy or mildewed under continuous exposure to moisture.

It is also another object of the present invention to provide a haystack cover which is non-porous and does not permit the stack to "breathe," so to speak, thereby reducing the free circulation or permeation of moisture-laden air through the dry haystack.

In the accompanying drawing—

Figure 1 is a perspective view of a haystack covered with a covering sheet constructed in accordance with and embodying the present invention;

Figure 2 is a fragmentary sectional view taken along line 2—2 of Figure 1;

Figure 3 is a fragmentary elevational view of the center ridge portion of the haystack cover;

Figure 4 is a fragmentary sectional view taken along line 4—4 of Figure 3;

Figure 5 is a fragmentary elevational view of the edge portion of the haystack cover;

Figure 6 is a fragmentary sectional view taken along line 6—6 of Figure 5 showing the hold-down rope in slack position; and

Figure 7 is a fragmentary sectional view taken along line 7—7 of Figure 1.

Fig. 8 is a fragmentary sectional view taken along line 8—8 of Fig. 1, and

Fig. 9 is a fragmentary sectional view taken along line 9—9 of Fig. 1.

Referring now in more detail and by reference characters to the drawing which illustrates a preferred embodiment of the present invention, A designates a haystack cover shown in Figure 1 in operative position upon a haystack B and fabricated of a large sheet 1 of laminated paper consisting of two plies 2, 2', of kraft or other high-tensile strength stock, secured together by a film or layer 3 of asphaltic adhesive, the latter prefer-

2

ably being provided with random length and random-located fibers 4 formed of sisal, hemp or other similar material.

Along its longitudinal center line the sheet 1 is folded up in the formation of a wide longitudinally extending ridge member 6. Folded over the ridge member 6 at spaced intervals along its length are U-shaped strips 7. Inserted through the ridge member 6 and strips 7 preferably adjacent each end and at the middle are eyelets or grommets 8 which are provided with relatively wide rims or flanges 9 and are clamped tightly in place. It should be noted that the outermost strips 7 and grommets 8 adjacent each end of the ridge 6 are spaced inwardly from the edges by a substantial distance and in such space the ridge 6 is provided with a strip 7' and two aligned grommets 8' so that the folds of the ridge 6 can be separated slightly, as shown in Figure 8.

Similarly the longitudinal margins of the sheet 1 are turned and adhesively secured in the provision of a hem 10 which is re-inforced by a U-shaped strip 11 folded around and secured thereto. Inserted through the strips 11 and hems 10 are eyelets 12 transversely aligned with the eyelets 8.

Threaded through each set of eyelets 12, 8, 12, and extending transversely across the sheet 1 are three hold-down cords or ropes 13 which can be pulled tightly down and tied around conventional stakes 14 driven into the ground when the cover is in operative position over the haystack B, as shown in Figure 1. If desired, a second haystack cover A can be "interleaved," so to speak, under the marginal edges of another such cover A, as shown in Figure 1, in which position the marginal end of one ridge 6 is inserted within the other ridge 6 and the four grommets 8' brought into axial alignment as shown in Figure 9. A hold-down rope 12 is threaded through such aligned grommets 8' and staked down.

It should be noted particularly that the ridge member 6 and its associated strips 7 stand up in more or less vertical position to form a sharp, clean watershed, and the eyelets 12 are tipped or cocked outwardly by the ropes 13, as shown in Figure 7, so that they bind and thus assist in holding down the edges of the sheet 1. It should also be noted that this out-turning of the edges tends to produce small eaves which deflect the rain water outwardly from the immediate base of the haystack B.

It should be understood that changes and modifications in the form, construction, arrangement, and combination of the several parts of the hay-

stack cover may be made and substituted for those herein shown and described without departing from the nature and principle of my invention.

Having thus described my invention what I now claim and desire to secure by Letters Patent is:

1. A haystack cover comprising a paper sheet having a central fold adapted to project upwardly during use to form an upstanding substantially vertical ridge, a series of spaced eyelets extending through said fold, eyelets also extending through the sheet along its marginal edges, each of such eyelets being aligned with one of the eyelets in the ridge-forming fold so as to form therewith a transversely aligned series of eyelets; and a hold-down rope threaded through each such transversely aligned series of eyelets.

2. A haystack cover comprising a paper sheet having a central fold adapted to project upwardly during use to form an upstanding substantially vertical ridge, a U-shaped cap strip adhesively secured over and along said ridge-forming fold, a series of spaced eyelets extending through said fold, eyelets also extending through the sheet along its marginal edges, each of such eyelets being aligned with one of the eyelets in the ridge-forming fold so as to form therewith a transversely aligned series of eyelets, and a hold-down rope threaded through each such transversely aligned series of eyelets, said fold being loose at both ends for interleaved engagement with the ridge-forming fold of another similar haystack cover when two such covers are disposed in end-to-end conjunction.

3. A haystack cover comprising a paper sheet having a central fold adapted to project upwardly during use to form an upstanding substantially vertical ridge, a U-shaped cap strip adhesively secured over and along said ridge-forming fold, a series of spaced eyelets extending through said fold, eyelets also extending through the sheet along its marginal edges, each of such eyelets being aligned with one of the eyelets in the ridge-forming fold so as to form therewith a transversely aligned series of eyelets, and a hold-down rope threaded through each such transversely aligned series of eyelets, said fold being loose at both ends for interleaved engagement with the ridge-forming fold of another similar haystack cover when two such covers are disposed in end-to-end conjunction, said fold being provided at its loose ends with axially aligned but independent eyelets.

4. A haystack cover comprising a paper sheet having a fold extending lengthwise and centrally thereacross and being adapted to project upwardly during use to form an upstanding substantially vertical ridge, a U-shaped cap strip adhesively secured over and along the external faces of said ridge-forming fold, a series of spaced eyelets extending through said fold, eyelets also extending through the sheet along its marginal edges, each of such eyelets being aligned with

one of the eyelets in the ridge-forming fold so as to form therewith a transversely aligned series of eyelets, and a hold-down rope threaded through each such transversely aligned series of eyelets.

5. A haystack cover comprising a large paper sheet provided with a first longitudinally extending fold line and two additional fold lines respectively disposed on opposite sides of, and in equidistantly spaced parallel relation to, the first fold line whereby to provide a U-shaped fold in which the areas between the first fold line and each of the two additional fold lines form inwardly presented contiguous faces and being adapted to project upwardly during use to form an upstanding substantially vertical ridge, a U-shaped cap strip adhesively secured over and along said ridge-forming fold, a series of spaced eyelets extending through said fold, eyelets also extending through the sheet along its marginal edges, each of such eyelets being aligned with one of the eyelets in the ridge-forming fold so as to form therewith a transversely aligned series of eyelets, and a hold-down rope threaded through each such transversely aligned series of eyelets, said fold being loose at both ends for interleaved engagement with the ridge-forming fold of another similar haystack cover when two such covers are disposed in end-to-end conjunction.

6. A haystack cover comprising a large paper sheet provided with a first longitudinally extending fold line and two additional fold lines respectively disposed on opposite sides of, and in equidistantly spaced parallel relation to, the first fold line whereby to provide a U-shaped fold in which the areas between the first fold line and each of the two additional fold lines form inwardly presented contiguous faces and being adapted to project upwardly during use to form an upstanding substantially vertical ridge, a U-shaped cap strip adhesively secured over and along said ridge-forming fold, said cap strip being substantially wider than the ridge-forming fold and thus being flanged outwardly on either side over and beyond said additional fold lines, a series of spaced eyelets extending through said fold, eyelets also extending through the sheet along its marginal edges, each of such eyelets being aligned with one of the eyelets in the ridge-forming fold so as to form therewith a transversely aligned series of eyelets, and a hold-down rope threaded through each such transversely aligned series of eyelets.
